UNITED STATES PATENT OFFICE.

WILLIAM E. HOKE, OF BALTIMORE, MARYLAND.

LAPPING MACHINE.

Original application filed August 30, 1918, Serial No. 252,073. Divided and this application filed December 9, 1922. Serial No. 605,972.

To all whom it may concern:

Be it known that I, WILLIAM E. HOKE, a citizen of the United States, residing at Baltimore, in the county of Baltimore and State of Maryland, have invented certain new and useful Improvements in Lapping Machines, of which the following is a specification.

This invention relates to an apparatus for 10 making articles of various kinds such as balls, cylinders, perforated articles, etc., of steel or iron, in large numbers, each article being of precisely the same dimensions as every other article.

15 Referring to the drawings:

Fig. 1 is a plan view on the plane I—I of Fig. 2;

Fig. 2 is a section on plane II—II of Fig. 1.

20 In carrying out my invention the articles are brought to final shape by lapping with a suitable lap which consists of a surface of wax, wood, lead, aluminum, copper, iron or steel having charged into its surface a suitable abradant such as emery, alundum, carborundum, etc.

25 In Figs. 1 and 2, 40 and 41 are annular cylindrical laps having true plane surfaces, the upper lap being arranged in any suitable manner to rotate about the axis. Mounted to be rotated, as by crank 45, eccentric to the axis of the lap, is a ring 42, having therein a series of circular openings within each of which are retained a number of the balls 44

30 to be ground. By the eccentric rotation of the plate 42 the balls are rotated and ground between the fixed and rotatory lapping surfaces. This ring 42, as shown, has a pivotal connection to the crank so that the plate is 35 free to revolve about its own axis. This pivotal connection is only diagrammatically illustrated, but any suitable connection may be used such as that shown in my prior application, Serial No. 242,482, filed June 28, 40 1918.

45 As shown, a number of balls are arranged about a central ball 46 which acts as a spacer to hold the balls away from the center of the opening in the ring. As the ring rotates in an eccentric planetary path, the balls are rolled over and over, and in turn impart a rotary movement to the upper lap.

50 The upper lap, which may of course be weighted if desired, is allowed to rest upon

the surface of the multiplicity of balls being 55 ground, and thus acts only to remove upstanding inequalities wherever they occur in the whole group of articles. The upper lap rests freely on the surfaces of the balls so that the grinding action is unrestrained. 60 This lap 40 may be kept in position by a ring 47 resting on the upper surface of the lap and having a central opening surrounding but of larger diameter than the crank, the ring 46 having a circular extension of 65 less diameter than the opening in the lap, so that the lap is kept in position but is none the less freely floating or unrestrained in movement.

65 After the first lapping operation, a certain number of the balls are transposed in position so that they occupy a different position with reference to the other balls, the lapping, transposition, and rearrangement of the balls being repeated until all are 70 brought to a uniform size.

75 The balls are measured after each lapping operation by placing a row of the balls in line as in a grooved receptacle, and the aggregate length of the row determined by 80 comparison with the standard. If the balls are still too large, they are, after being transposed in their relative positions, subjected to as many lapping operations as may be required to reduce them to exact size. 85

85 This application is a division and continuation of my application Serial No. 252,073, filed August 30, 1918.

I claim:

1. A lapping machine comprising a pair 90 of discs having spaced lapping surfaces, a work carrier between said discs having a plurality of apertures therein, and means for effecting bodily movement between the work carrier and the laps in a substantially 95 circular path, said machine having one lap unrestrained in movement and each of the openings in the work carrier being of a size to loosely hold a plurality of articles to be lapped.

100 2. In a lapping machine, a pair of discs having spaced lapping surfaces, one of said laps being unrestrained in movement a work carrier between said discs, said work carrier having a plurality of apertures for loosely holding articles to be lapped, with means for separating a group of the articles being operated upon, a crank connected to said

carrier and arranged to impart movement to said carrier eccentric to the axis of the discs.

3. In a lapping machine, a pair of discs having spaced lapping surfaces, a work carrier between said discs, and means for effecting a relatively eccentric planetary movement between said carrier and said discs, said carrier being also rotatable about its own center, and said work carrier having a plurality of apertures for loosely holding articles to be lapped, with means for separating the members of a group of the articles being operated upon.

4. In a lapping machine, a pair of discs having spaced lapping surfaces, a work carrier between said discs, and means for effecting a relatively eccentric planetary movement between said carrier and said discs, said carrier being also rotatable about its own center, and said work carrier having a plurality of apertures for loosely holding

articles to be lapped, with means for holding said articles away from the centers of said apertures.

5. A lapping machine including in combination two opposed laps having flat working surfaces, a work carrier positioned between said laps and having work receiving openings therein, each of said openings being of a size to hold a plurality of articles to be lapped, a shaft having a crank centrally loosely engaging the work carrier, whereby the work carrier is free to rotate about its own axis and there results bodily movement between the work carrier and laps in a circular path, the plurality of articles in each opening in the work carrier being free to rotate bodily about the axes of the openings so as to execute a substantially planetary movement.

In testimony whereof, I affix my signature.

WILLIAM E. HOKE.
